(57) **CLAIM**

The ornamental design for an idler roller, as shown and described.

DESCRIPTION

FIG. 1 is a perspective view of an idler roller showing our new design.

FIG. 2 is a cross-section view of the idler roller shown in FIG. 1.

FIG. 3 is a side view of the idler roller shown in FIG. 1.

FIG. 4 is an end view of the idler roller shown in FIG. 1.

FIG. 5 is a perspective view of an idler roller showing our new design.

FIG. 6 is a cross-section view of the idler roller shown in FIG. 5.

FIG. 7 is a side view of the idler roller shown in FIG. 5.

FIG. 8 is an end view of the idler roller shown in FIG. 5.

FIG. 9 is a perspective view of an idler roller showing our new design.

FIG. 10 is a cross-section view of the idler roller shown in FIG. 9.

FIG. 11 is a side view of the idler roller shown in FIG. 9.

FIG. 12 is an end view of the idler roller shown in FIG. 9.

FIG. 13 is a perspective view of an idler roller showing our new design.

FIG. 14 is a cross-section view of the idler roller shown in FIG. 13.

FIG. 15 is a side view of the idler roller shown in FIG. 13.

FIG. 16 is an end view of the idler roller shown in FIG. 13.

FIG. 17 is a perspective view of an idler roller showing our new design.

FIG. 18 is a cross-section view of the idler roller shown in FIG. 17.

FIG. 19 is a side view of the idler roller shown in FIG. 17.

FIG. 20 is an end view of the idler roller shown in FIG. 17.

FIG. 21 is a perspective view of an idler roller showing our new design.

FIG. 22 is a cross-section view of the idler roller shown in FIG. 21.

FIG. 23 is a side view of the idler roller shown in FIG. 21.

FIG. 24 is an end view of the idler roller shown in FIG. 21.

FIG. 25 is a perspective view of an idler roller showing our new design.

FIG. 26 is a cross-section view of the idler roller shown in FIG. 25.

FIG. 27 is a side view of the idler roller shown in FIG. 25.

FIG. 28 is an end view of the idler roller shown in FIG. 25.

FIG. 29 is a perspective view of an idler roller showing our new design.

FIG. 30 is a cross-section view of the idler roller shown in FIG. 29.

(Continued)

FIG. 31 is a side view of the idler roller shown in FIG. 29;
and,

FIG. 32 is an end view of the idler roller shown in FIG. 29.
The broken lines in the drawings depict unclaimed environmental subject matter.
